THE COLUMBIA PLANOGRAPH CO., WASHINGTON, D. C.

UNITED STATES PATENT OFFICE.

CHARLES L. RAYFIELD, OF CHICAGO, ILLINOIS, ASSIGNOR TO FINDEISEN & KROPP MANUFACTURING COMPANY, OF CHICAGO, ILLINOIS, A CORPORATION OF ILLINOIS.

CARBURETER.

1,313,332.

Specification of Letters Patent.

Patented Aug. 19, 1919.

Application filed April 16, 1914. Serial No. 832,158.

To all whom it may concern:

Be it known that I, CHARLES L. RAYFIELD, a citizen of the United States, and a resident of the city of Chicago, in the county of Cook and State of Illinois, have invented certain new and useful Improvements in Carbureters; and I do hereby declare that the following is a full, clear, and exact description of the same, reference being had to the accompanying drawings, and to the numerals of reference marked thereon, which form a part of this specification.

This application relates to improvements in carbureters of the type shown in my patent for "multiple jet carbureters", No. 1,224,207, dated May 1, 1917.

It is an object of this invention to construct a multiple jet carbureter wherein certain of the needle valves are connected to the throttle of the carbureter for simultaneous actuation therewith, and other valves for the inlet of fuel are connected to the automatic air inlet valve to be opened simultaneously therewith.

It is also an object of the invention to afford a construction of the class described in which air inlet ports are provided for each jet positioned to conduct the air across the jet when in operation.

It is a further objection of the invention to afford a construction in which a residual supply of gasolene or other hydrocarbon fuel is maintained at all times in the path of the inflowing air to assist in initial carburation and to afford a large vaporizing area exposed to the inflowing air.

It is also an object of the invention to afford a construction adapted for ready adjustment to insure satisfactory operation at high and low speeds of the engine.

It is a further object of this invention to construct a carbureter wherein a plurality of fuel inlet valves are connected for independent operation, one connected to be actuated simultaneously by actuation of the throttle valve and another by movement of the automatic air inlet valve and with means in combination with said inlet valve to force a fuel under pressure through said fuel valves.

It is also an object of this invention to construct a carbureter in which the level of the fuel in the float chamber may be momentarily raised, due to a sudden open-

ing of the throttle valve to augment the flow 55 of fuel through the supply valve and facilitate acceleration of the motor.

It is also an object of this invention to construct a carbureter embodying a plurality of fuel inlet valves independently 60 operable but each communicating with a common source of fuel supply, and with means for augmenting the pressure in the fuel supply with an opening of the automatic air inlet valve of the carbureter to 65 force a fuel through said respective fuel valves under pressure.

It is furthermore an object of this invention to construct a carbureter wherein a fuel valve is connected to an automatic air 70 inlet valve for simultaneous actuation therewith and with a dash pot mechanism for preventing fluttering of the inlet valve and fuel valve and acting to force fuel under pressure through said fuel valve when said 75 valve is opened by said air valve.

It is finally an object of this invention to construct a multiple jet carbureter embodying a plurality of independently operable fuel supply valves as well as means 80 acting automatically to augment the pressure to force fuel through said valves with a sudden opening of the automatic air inlet valve of the carbureter, and each of said fuel valves and air valves constructed 85 for adjustment to suit varying conditions of operation.

My invention also has other important objects which will appear from the following specification and the accompanying 90 drawings.

The invention (in a preferred form) is illustrated in the drawings and hereinafter more fully described.

In the drawings:

Figure 1 is a side elevation of a carbureter embodying the principles of my invention.

Fig. 2 is a similar view of the other side thereof.

Fig. 3 is a view similar to Fig. 2, but showing a view in central section taken through the carbureter.

Fig. 4 is a view similar to Fig. 3, showing a modified form.

Fig. 5 is a fragmentary central vertical section taken through the air inlet end of the carbureter.

Fig. 6 is a fragmentary section taken on line 6—6 of Fig. 4, with parts omitted.

Fig. 7 is an enlarged detail sectional view of the fuel inlet valve connected to the air valve of the carbureter.

Fig. 8 is a section taken on line 8—8 of Fig. 7.

Fig. 9 is a fragmentary top plan view of the lever connections on the carbureter.

10 As shown in the drawings:

The carbureter comprises an integral casting affording a float feed chamber 1, and a mixing chamber 2. The casing of the float feed chamber 1 comprises cylindrical side walls and an integral bottom wall 3, having a central or axial downwardly directed tubular boss 4, integral with the bottom thereof and opening upwardly thereto. Said boss is closed at its lower end by means of a screw plug 5, threaded thereto and engaging a suitable packing washer 6, between the same and the end of said boss to seal the connection. The cover 7, for the float feed chamber is removably secured thereto and extending 25 axially through said chamber and a suitable central aperture in said cover 7, is a rod 8, of a length to extend into the bore in said boss 4, as shown in Figs. 3 and 4, and to normally extend slightly above the cover 30 through an aperture therein. Adjustably but rigidly secured on said rod is a float 9, in the present instance shown as constructed of sheet metal, and having a sleeve 10, extending centrally therethrough, and through 35 which the rod 8, extends. Said float feed chamber is cored in the side adjacent the mixing chamber to register with an inward extension A, of the chamber in the space between the same and said mixing chamber, 40 and, as shown, the casing of the mixing chamber 2, is constructed to afford a similar chamber B, extending over said chamber A. The bottom of said chamber A, of the float feed chamber, is provided with an aperture 45 therethrough, and threaded therein at its upper end is a cylindric plug 11, which serves to close the bottom of that portion of the float feed chamber and is provided with a central upwardly opening recess or bore 50 therein, communicating with a restricted central bore extending therethrough, which affords the seat for the inlet needle valve 19, through which the flow of the hydrocarbon fuel into the float feed chamber is controlled. Said plug is provided on its lower 55 end with a peripheral downwardly extending internally threaded flange 12, and threaded thereto is a hollow connection 13, having a screen 14, stretched across the top 60 thereof.

The induction pipe 15, whereby the gasoline tank communicates with the float feed chamber, is threaded into said connection 13. The horizontal partition 16, between the extension B, of the mixing chamber and the

extension A, of the float feed chamber, forming the bottom of one and the top of the other, is provided with an aperture therethrough and threaded therein in alinement with the corresponding seat in the plug 11, 70 is the tubular nozzle or jet pipe 17, the upper end of which extends above the partition 16, in said extension of the mixing chamber, and the lower end of which extends below said partition 16. Slidably and loosely engaged thereon in the extension A, of the float feed chamber is a sleeve 18, which, near its lower end, is restricted and tapered to a point to afford the valve closure 19, to seat within and to close the induction passage 80 through the plug 11. Said sleeve 18, is provided with apertures 18a, therein slightly above the bottom of the float feed chamber to admit the fluid from said float chamber thereto, and a peripheral flange 20, is provided on said sleeve intermediate its end as shown in Fig. 3. A weak spring 21, is engaged around said sleeve and bears at its upper end against the wall 16, and at its lower end on said flange to hold the lower 90 needle valve 19 normally closed when the float feed chamber is sufficiently full to support the float.

Removably secured in the float feed chamber on the bottom thereof is a bracket 22, and pivotally engaged thereon is a lever 23, the shorter end of which is yoked to engage around the sleeve 18 below the flange 20, and the longer end of which is provided with an aperture therethrough to receive the rod 8. 100 As shown, a diametrically apertured ball 24, is rigidly secured on said rod 8, and seats on said longer end of the lever 23, to afford a self-adjusting bearing for the float on said lever. Said plug 11, is provided with a passage 25, extending downwardly from its inner end to a passage 26, extending peripherally from the same. A pipe 27, is at one of its ends threaded into said plug 11, and communicates with said passage 26, and at its other end is threaded into the lower end or extension forming a dash pot 28, of an air-inlet valve casing 29, which is threaded on a horizontally directed portion of the inlet to the mixing chamber 2.

Integral with the wall of the mixing chamber and directed toward the float feed chamber is a bracket or arm 30, having a cylindric seat in the underside thereof co-axial with the bore of the jet nozzle 17, and engaged therein at its upper end and extending through the top wall 31, of the extension B, of the mixing chamber is a needle valve closure 32, for said jet nozzle 17. A spring 33, engaged in said seat in the arm 30, bears on the upper end of said needle valve to hold the same normally seated.

Journalized in a suitable bearing on the wall of the mixing chamber is a transverse shaft 34, and secured thereon and project- 130

ing into a slot in the stem of the needle valve closure 32, is a finger 35, which acts with the rotation of said shaft 34, to raise said needle valve closure against the tension 5 of said spring 33. At the upper end of the casing affording the mixing chamber is provided an outwardly extending flange 36, which may be apertured to afford engagement with the manifold pipe leading to 10 the engine. Extending through said mixing chamber is a shaft 37, parallel to shaft 34, above the extension B, of the mixing chamber, and rigidly but adjustably secured thereon is a butterfly valve closure 38. The 15 butterfly valve closure 38, is slightly cut away on one side thereof to afford a sufficient passage for the mixture to the manifold pipe to support combustion when the throttle is substantially closed or at its lowest 20 running adjustment. Secured on the outer end of the shaft 37, is a throttle lever 39, whereby said shaft may be rotated and said butterfly valve adjusted. Also rigidly secured thereon is a rectangular block 25 40, at the inner side of the throttle lever and slidably and adjustably secured thereon is a cam 41, comprising cam faces arranged approximately at right angles to each other and the angle corner portion which would 30 be formed thereby cut away to afford a rounded continuation of the cam, as clearly shown in Fig. 1.

A screw shaft 42, journaled in the ends of said cam block, is threaded through said 35 block 40, and extending through a notch in the shaft 37, is provided on its outer end with an adjusting head 43, whereby the cam may be shifted on said block 40, with reference to its center of rotation, to-wit the 40 shaft 37.

Loosely engaged on the shaft 34, for adjusting the needle valve closure 32, is a downwardly and forwardly extending arm 44, provided at its forward end with a bearing plate 45, removably secured thereon and engaging said movable cam member 41, and adapted by engagement therewith to actuate said lever and the shaft 34, to operate said needle valve. Integral with the arm 44, is 45 a downwardly extending arm 46, provided with a set screw 47, extending therethrough and rearwardly beyond the same.

Rigidly secured on said shaft 34, by means 50 of a bracket arm 48, is a tubular element 55 49. Journaled in said element is a shaft having rigidly secured on the lower end thereof a cam or eccentric 50, which bears against the rearwardly extended end of the set screw 47, and provides engagement 60 whereby the bracket arm 48 and shaft 34, are operated to regulate the fuel valve 32, by the movement of the levers 44 and 46. Slight movement of the shaft 34, is thus 65 permitted independently of the movement of the arms 44 and 46, by rotation of the

cam 50, against the adjusting screw which serves to swing the lower end of the sleeve or tubular element 49, forwardly, thereby elevating the finger 35, secured on said shaft on the interior of the carburetor and slightly 70 opening the needle valve 32 and admitting to the extension B, of the mixing chamber a supply of fuel. Secured upon the upper end of the shaft contained within the tubular element 49, is a lever 51, and an actuating rod 52, is connected thereto at the extremity thereof by means of a set screw 53, and said actuating rod 52, extends slidably through a bracket 54, mounted on the cover of the float feed chamber. 80

Rigidly secured on the end of the shaft 37, at the opposite side of the carburetor is an arm 55, provided with a set screw 56, adapted to engage on a projection or lug 57, on the outer wall of the mixing chamber, 85 as clearly shown in Fig. 2. As shown, a set screw 58, is employed for engaging said arm 55, on the shaft. Said set screws 56 and 58, afford means for adjusting said arm to limit the degree of closure of the butterfly valve to the required amount to maintain a sufficient supply of mixture to the motor to maintain the combustion at the lowest speed of the motor. 90

A supply of air is provided for the inlet 95 jet 17, and this is admitted through an inlet port provided in the extension B, of the mixing chamber slightly at the rear thereof, and a peripheral flange or tubular extension 59, in the wall of the casing is provided 100 around said port and extends outwardly substantially flush with the side walls of the casing as shown clearly in Fig. 2. The passage therethrough tapers inwardly to conduct the air in a strong inflowing current or jet against the jet of hydro-carbon as it comes from the needle valve, thus spraying and thoroughly vaporizing the same and carrying the same therewith into the mixing chamber 2, beneath the butterfly 110 valve 38. As shown also in Fig. 3, a slight elevation or rib 60, is provided on the floor of the extension B, of the mixing chamber at the point where the same communicates in the main mixing chamber, thereby serving 115 to maintain a thin film or layer of the hydrocarbon fuel on said floor 16, to expose a large surface to vaporization.

Another inlet fuel valve or nozzle is provided within the air inlet casing 29, and 120 this comprises a tubular member 61, which is threaded into the top wall of the dash pot chamber 28, and extends downwardly therethrough communicating therein at its lower end through an apertured plug 62. 125

A perforated cap 63, is secured around the upper end of said tubular member 61, and slidably mounted therein and through the upper end of a tapered aperture in said tubular member is a tapered valve member 130

64. Said tapered valve closure 64, is held normally in closed position by means of a coiled spiral spring 65, seated on the plug 62, in the lower end of said tubular member, and at its upper end said spring bears against a spider 66, integral with an upwardly extending rod 67, which is rigidly engaged in the lower end of said valve closure 64.
- 10 An air inlet port is provided to deliver inflowing air to and across the top of the jet nozzle 63. For this purpose as shown a suitable aperture is provided in the upper wall of the casing 29, and threaded thereinto is an outwardly flaring casing 68, affording an inner seat against which a conical disk air inlet valve closure 69, is adapted to rest. An elongated tubular boss 70 is formed axially within said casing 29, and wound therearound and seating at its lower end on said boss is a spiral compression spring 71, which at its upper end seats within a recessed portion of said valve closure 69, to normally hold the same in closed position. A valve stem 72, is rigidly secured in said closure 69, and is slidably mounted within said tubular boss 70, with the lower end of said stem extending into the dash pot chamber 28, and secured on said lower end is a piston 73, adapted to move within said dash pot chamber and apertured to receive the tubular element 61, therethrough.
- 15 A contact screw 74, is threaded through one side of said valve closure 69, and is adapted to contact the upper end of said closure 64, to depress the same with a downward or opening movement of said closure 69, and inasmuch as said contact screw is threaded into the aperture 69, it may be 20 adjusted to contact the closure 64, at any predetermined time.
- 25 As shown, the outer periphery of said flared casing 68, is fluted, and a spring detent 75, is mounted in an extension 76, formed on said casing 29, to hold said flared adjustable casing 68, in an adjusted position. Of course, when the casing is adjusted inwardly the compression of the spring against the closure 69, is increased 30 thereby, while outward adjustment decreases such pressure, thereby allowing the air inlet valve to open at any desired predetermined draft or difference of pressures.
- 35 As shown, a tubular casing or hood 77, closed at its upper end is threaded upon a central raised boss 78, on the cover of the float feed chamber to exclude dust and dirt therefrom. Said boss, as shown, is also provided with a vent passage 79, there- 40 through from the float feed chamber to vent said chamber against internal pressure. Pivottally engaged in said hood and extending through a slot in the side wall thereof is a bent lever, one arm 80, of which ex- 45 tends over and into position to engage the
- rod 8, when the float feed chamber is filled to normal capacity. The other arm 81, of said lever extends downwardly on the outer side of said hood and is engaged by a suitable rod to permit manual actuation thereof 50 holding the rod 8, with the float thereon downwardly until the carburetor is slightly flooded to facilitate starting carburation. A spring 82, is engaged on said lever and acts to hold the arm 80, upwardly out of 55 position out of contact with said rod 8, as clearly shown in Fig. 3. As clearly shown in Fig. 3, the carburetor casing is cored around the mixing chamber to afford an exterior water jacket denoted as a whole by the 60 reference numeral 83, which may be connected to the radiator of the engine if desired. However, such a water jacket may or may not be provided, depending in part on the size of the carburetor, the capacity 65 required and the character or use for which intended.
- 66 In the modification of my device illustrated in Fig. 4, I provide two parallel shafts 84 and 85, respectively, in a mixing chamber 2, which is open at its lower end, as indicated by the reference numeral 86, said shafts mounted above and below the extension B, of the mixing chamber respectively. Rigidly but adjustably secured on 70 said shafts are the respective butterfly valves 87 and 88. The upper butterfly valve closure 87, as pointed out may be slightly cut away on one side thereof to afford a sufficient passage for the mixture to the manifold pipes to support combustion when the throttle is substantially closed or at its lower running adjustment. The lower throttle lever 88, is provided with an upwardly extending boss or projection 89, to which is 75 pivotally engaged the lower end of a link 90, the upper end of which is pivotally engaged on a rigid bracket arm 91, secured at its other end upon the extended tubular portion 92, of the automatic air inlet valve 100 closure 69. Said rigid bracket arm 91, is provided with an aperture 94, to receive the valve closure 64, therethrough and is of sufficient size to slide downwardly around the top 63, and upper portion of the tubular 105 element 61, with a downward movement of said air inlet valve closure 93.
- 110 The operation is as follows:
- 115 The carburetor having been assembled and suitably connected with the manifold pipes 120 of the engine, and with the fluid supply pipe from the tank, is adjusted to regulate the air supply through the automatic valve 69, and to regulate the inlet of the jet nozzle 17, in the extension B of the mixing chamber. The adjustment for said needle valve is effected by turning the set screw 47, to vary the normal relation of the lever arm 46, and tubular bracket 49, which adjustment 125 enables the required amount of fuel to 130

be obtained for idling or low speed, and further adjustment may be had by turning the set screw 43, and moving the cam 41. This latter adjustment is effective only after 5 the throttle has been opened somewhat and is therefore adapted to regulate the supply of fuel for medium and high speed. Thus a wide range of adjustment is afforded, providing regulation for high and low speed, 10 and moreover the fuel supply may be increased at any time by pulling on the rod or wire 52, and rotating the shaft in the tubular bracket 49, and with it the cam 50 which bears against the set screw 47, and 15 thereby shift the tubular bracket 49, and the shaft 34, and raises the valve 30, to admit an abnormal supply of fuel through the nozzle 17, although this adjustment is designed particularly to be used in starting 20 the motor. This is also facilitated by means of the tickler lever on the float feed chamber whereby the float may be held depressed and the inlet valve 19, held open to permit flooding of the float feed chamber. The automatic 25 air inlet valve 69 of course is adjusted so that normally said valve remains closed. By adjusting the flaring casing 68 for said automatic valve inwardly or outwardly substantially any air inlet requirement for cer- 30 tain differences of pressure may be attained. The adjustment of the needle valve closure 32, within the extension B, of the mixing chamber is such as to maintain a low engine rate of speed, as when the engine is 35 idling, the mixture escaping therefrom to the manifold pipe through the cut away portion in the edge of the butterfly valve closure 38, which is just above the mouth of the extension B, of the mixing chamber, 40 when said butterfly valve is closed. As the throttle valve is opened wider the draft of the engine increases, thereby causing an opening of the automatic air inlet valve and consequently an opening of the fuel supply 45 valve positioned in the inlet casing 29. In each case the air admitted to the carburetor blows directly across the fuel inlet, thereby easily vaporizing the fuel and then passing on into the mixing chamber. A secondary 50 action also takes place with a sudden opening movement of the automatic air inlet valve due to the sudden depression of the piston 73, connected thereon. The chamber in which the piston operates is below the 55 normal level of the fuel in the float chamber of the carburetor and as the chambers are in communication through the pipe 27, the piston chamber is kept filled with the fuel liquid. This is made possible by the some- 60 what loose engagement of the piston with the walls of the piston chamber and with the sleeve 61, which loose engagement enables the fuel to pass above the piston, and is also due to the necessarily free engage- 65 ment of the stem 72, with the bore of the sleeve or hub 70, which furnishes a compensating passageway from the upper part of the piston chamber and prevents pocketing of air therein and permits complete filling thereof with the fuel, and also provides 70 relief therefor as the piston is forced downwardly. As the piston moves downwardly in the chamber 28, the valve 64 is opened and simultaneously pressure is applied to the fuel liquid below the piston which forces 75 the fuel upwardly and out through the nozzle 61, and at the same time, on account of the connection of the pipe 27 with the piston chamber and float chamber, raises slightly the level of the fuel in the float 80 chamber and augments the supply of fuel through the nozzle 17, so that both nozzles provide an increased supply of fuel and a rich mixture results which enables the engine to be accelerated instantly in response 85 to a sudden opening of the throttling valve.

In the modified form of my device illustrated in Fig. 4, I have shown two entrance passages for air, the one 86, in the lower end of the mixing chamber controlled by a 90 butterfly valve 88, and the other past the automatic inlet valve 93. However, owing to the linked connection between said automatic valve 93, and the butterfly valve 88, movement of said automatic valve is imme- 95 diately transmitted to the butterfly valve to open the same, so that with a sudden draft through the carburetor by the engine fuel is supplied to the mixing chamber from the nozzle 17, and as well through the nozzles 100 63. The vaporized fuel passes from said nozzle to the mixing chamber and is intermingled with a quantity of air entering through the lower end of said chamber, the mixture then flowing past the throttle valve 105 87, to the manifold of the engine. As before, a dash pot 28, with a piston 73, movable therein and connected to the air valve is provided, and acts in exactly the same manner to augment the pressure throughout the 110 fuel supply chambers of the carburetor to force the fuel under pressure through the respective fuel nozzles with a sudden opening movement of the automatic air valve 93.

It is to be understood of course that details of construction may be varied through a wide degree. I have shown a preferred form of my invention, although numerous modifications and variations thereof are of course possible. I therefore do not purpose 115 limiting the patent granted otherwise than necessitated by the prior art.

I claim as my invention:

1. A carburetor embodying a float feed chamber, a mixing chamber, jet nozzles 120 therefor adapted to admit a hydro-carbon fluid, a throttle valve, means for regulating the inlet from one of the nozzles simultaneously and correspondingly with the adjustment of the throttle valve, ports for ad- 125

mitting air into the mixing chamber across the discharge for the nozzles, an automatically operated normally closed valve for one of said ports, a dash pot connected therewith, said dash pot being in communication with the float feed chamber to maintain a supply of fuel in the dash pot, one of said jet nozzles communicating in said valve air port, and a piston movable in said dash-pot 10 chamber and connected to said air valve to prevent fluttering thereof and to augment the pressure in the fuel supply of the carbureter to force the fuel under pressure through said respective jet nozzles.

15 2. A carbureter embodying a mixing chamber, a float feed chamber, a dash pot chamber communicating with said float feed chamber, a plurality of fuel inlet nozzles, one connected with the float feed chamber 20 and the other with said dash pot chamber, a throttle valve, an adjustable cam connected therewith for regulating the inlet from one of the nozzles simultaneously with the adjustment of the throttle valve, a plurality 25 of ports for admitting air into the mixing chamber, each one thereof directing the air across one of said nozzles, an automatically operating normally closed air valve controlling one of said ports, a piston connected 30 to said air valve and mounted in said dash pot chamber to prevent fluttering of said valve and acting under a sudden opening of the air valve to augment the pressure in said dash pot chamber and float feed chamber 35 to force fuel through said nozzles under pressure.

3. In a carbureter, a mixing chamber, a nozzle for spraying the hydro-carbon fluid thereinto, air inlet ports, a throttle valve, a 10 normally closed air valve controlling one of said ports, connections between the throttle valve and said hydro-carbon nozzle, and a dash pot connected with said air valve acting to augment the pressure in the fuel supply to force hydro-carbon through said fuel nozzle, under pressure.

4. In a carbureter, a source of fuel, a mixing chamber, means for discharging the hydro-carbon fluid thereinto at a plurality 50 of different points, a float valve controlling the flow of fuel to said points, air inlet ports, a throttle valve, a normally closed air valve controlling one of said ports, connections between said throttle valve and one 55 of said hydrocarbon fluid means, and dash pot connections between said air valve and the source of fuel causing an augmentation of pressure in the fuel supply source of the carbureter with a sudden opening of the air 60 valve.

5. In a carbureter, the combination with the throttle valve, of a normally closed inlet air valve, a cam actuated hydro-carbon needle valve, connections between the same 65 and said throttle valve to cause said throt-

tle and needle valves to open proportionately, a second hydro-carbon inlet valve disposed adjacent said air valve, and mechanism connected with said air valve to force fuel through said respective hydro-carbon 70 inlet valves under pressure.

6. In a carbureter, the combination with a casing provided with a mixing chamber, of a hydro-carbon inlet valve, a normally open air inlet port therefor, a normally closed 75 air inlet valve, a hydro-carbon inlet valve mounted adjacent thereto and connected for simultaneous operation therewith, dash pot means connected with said air valve to force fuel through said respective hydro-carbon 80 inlets with a sudden opening of said air valve, a throttle valve, and adjustable connections between said first mentioned hydro-carbon inlet valve and said throttle valve to open the same proportionately with an opening 85 of said throttle valve.

7. In a carbureter, the combination with a casing provided with a mixing chamber, of a valved hydro-carbon inlet, a normally closed air inlet valve, a second hydro-carbon 90 inlet positioned adjacent thereto, dash pot mechanism connected with said air inlet valve and adapted under a sudden opening of said air inlet valve to force fuel through said respective hydro-carbon inlets under 95 pressure, a throttle valve, and adjustable connections between said throttle valve and said first mentioned hydro-carbon inlet valve to cause a proportionate opening of said inlet valve with an opening of the throt- 100le valve.

8. The combination with a carbureter and its needle and throttle valves, of a normally closed air valve controlling a passage to the mixing chamber of the carbureter, a cam 105 connected on said throttle valve to actuate said needle valve, a dash pot chamber, a valved hydro-carbon inlet communicating therein, mechanical connections between said air valve and said hydro-carbon inlet valve 110 to open said inlet valve with an opening of said air valve, said dash pot mechanism acting to force fuel under pressure through said respective needle and hydro-carbon inlet valves with an opening movement of said 115 air valve.

9. In a carbureter, the combination with a throttle valve, a plurality of normally-closed air inlet valves, a cam-actuated hydro-carbon needle valve, connections between the 120 throttle valve and the needle valve to cause said needle valve to open proportionately with the opening of the throttle valve, and a second hydrocarbon inlet valve co-operating with both of said inlet air valves to open 125 therewith and operating independently of said cam-actuated needle valve.

10. In a carbureter, a mixing chamber, a cam actuated hydro-carbon inlet valve, a normally closed spring actuated air valve 130

controlling an inlet passage to said mixing chamber, a hydro-carbon inlet adjacent thereto, connections between said throttle valve and the first mentioned hydro-carbon 5 inlet valve to cause said valves to open proportionately with an opening of the throttle valve, and dash pot mechanism connected with said spring actuated air valve to force fuel under pressure through each of said 10 respective hydro-carbon inlets with an opening of said air inlet valve.

11. In a carbureter, the combination of a casing provided with a main mixing chamber, an auxiliary mixing chamber communicating therewith, a passage leading to said main mixing chamber and disposed oppositely from said auxiliary mixing chamber, hydro-carbon inlets one in said auxiliary mixing chamber and the other in said passage 20 leading to the main mixing chamber, a throttle valve controlling the outlet from said main mixing chamber, connections between said throttle valve and the hydro-carbon inlet in said auxiliary mixing chamber, 25 a normally closed spring actuated air valve controlling the admission of air to said passage, and connections between said air valve and said second mentioned hydro-carbon inlet valve in said passage to cause an opening 30 of the latter valve with an opening of said air valve.

12. In a device of the class described, a float feed chamber, a mixing chamber, an air inlet chamber, a dash pot chamber, an 35 inlet fuel valve mounted in said air inlet chamber communicating with said dash pot chamber, a hydro-carbon inlet valve mounted to control the inlet of fuel from said float feed chamber to said mixing chamber, a 40 throttle valve in said mixing chamber, and connections between said throttle valve and said second mentioned inlet valve to cause proportionate movement of each with a movement of the throttle valve, and an air 45 valve mounted in said air inlet chamber adapted to actuate the hydro-carbon fuel inlet therein when said air valve is opened.

13. In a device of the class described, a mixing chamber, a float feed chamber, a 50 dash pot chamber in communication with said float feed chamber to receive fuel therefrom, an air inlet chamber communicating with said mixing chamber, a hydro-carbon inlet valve mounted between said float feed 55 chamber and said mixing chamber to admit fuel from the float chamber to the mixing chamber, a throttle valve in said mixing chamber, connections between said throttle valve and said hydro-carbon inlet valve to 60 cause proportionate movement of the latter with the movement of the throttle valve, an air inlet valve mounted in said air inlet chamber, a piston connected therewith and mounted in said dash pot chamber to augment 65 the pressure in said chamber and in

said float feed chamber with a sudden opening movement of said air valve, and a hydro-carbon inlet valve mounted in said air inlet chamber adapted for positive actuation by said air valve to receive fuel therethrough 70 under pressure from said dash pot chamber with a sudden opening of the air valve.

14. In a device of the class described, a mixing chamber, a float feed chamber, a dash pot chamber in communication with 75 said float feed chamber to receive fuel therefrom, an air inlet chamber communicating with said mixing chamber, a hydro-carbon inlet valve mounted between said float feed chamber and said mixing chamber to admit 80 fuel from the float chamber to the mixing chamber, an air inlet valve mounted in said air inlet chamber, a piston connected therewith and mounted in said dash pot chamber to augment the pressure therein and in said 85 float feed chamber with a sudden opening movement of said air valve, a hydro-carbon inlet valve mounted in said air inlet chamber, and adjustable means on said air valve to actuate said latter inlet valve to admit 90 fuel therethrough under pressure from said dash pot chamber with a sudden opening of the air valve.

15. In a device of the class described, a mixing chamber, a float feed chamber, a dash pot chamber in communication with 95 said float feed chamber to receive fuel therefrom, an air inlet chamber communicating with said mixing chamber, a hydro-carbon inlet valve mounted between said float feed 100 chamber and said mixing chamber to admit fuel from the float chamber to the mixing chamber, a throttle valve in said mixing chamber, an air inlet valve mounted in said air inlet chamber, a piston connected therewith and mounted in said dash pot chamber to augment the pressure therein and in said 105 float feed chamber with a sudden opening movement of said air valve, and a hydro-carbon inlet valve mounted in said air inlet 110 chamber adapted for positive actuation by said air valve to receive fuel therethrough under pressure from said dash pot chamber with a sudden opening of the air valve.

16. In a carbureter of the class described, 115 two air inlet ports, one thereof having a constant opening of unvarying area, an automatically acting valve for the other of said ports normally closing the same, a fuel inlet adjacent each of said air inlet ports, 120 means operable by said valve for varying the area of one of said fuel inlets, a cylinder and piston comprising a dash-pot adapted to supply fuel to one of said fuel inlets, and means connecting the piston of said dash-pot with said valve to force fuel through said inlet when said valve is opened.

17. In a carbureter having a mixing chamber, an air inlet of constant area, and an auxiliary air inlet, the combination of a suc- 130

- tion operated valve for automatically regulating the capacity of the auxiliary inlet, a fuel chamber having an outlet into the mixing chamber, a valve for said outlet 5 operated with the suction valve for regulating the supply of fuel proportionately to the capacity of the auxiliary air inlet, an auxiliary fuel chamber, and a plunger therein operable with the suction operated air valve and fuel outlet valve to inject a supply of fuel into the mixing chamber.
18. In a carbureter of the class described, a carbureting chamber, air inlet ports therefor, a butterfly valve for one inlet port, an 10 automatic valve mounted in the other air port normally closing the same and disposed at one side of said carbureting chamber, a float chamber for fuel, mechanism connecting the automatic valve and the butterfly valve whereby the automatic valve also automatically operates the butterfly valve, an auxiliary fuel chamber communicating with said float chamber and alined beneath said automatic valve, a piston in said auxiliary 15 chamber, and means connecting said piston with said valve for momentary rise of the pressure of fuel in said auxiliary chamber with a sudden opening of said valve to which said piston is connected.
19. In a carbureter of the class described, a mixing chamber, a plurality of air inlets therefor, fuel inlet means mounted adjacent each of said air inlets, one of said air inlets normally open and of constant area, the 20 other of said inlets normally closed, means varying the area of discharge of said fuel inlet adjacent said normally closed air inlet, and dash-pot mechanism connected with said means to augment the pressure of fuel 25 when said normally closed air inlet port is suddenly opened.
20. In a carbureter, a carbureting chamber, two air ports, a butterfly valve for one side thereof, a suction operated valve for 30 the other disposed at one side of said carbureting chamber out of alinement therewith, a float feed fuel supply chamber, an auxiliary fuel chamber disposed in alinement with said suction operated valve and 35 communicating with said float feed chamber, a piston in said auxiliary fuel chamber, a stem rigidly connecting said piston and said suction valve for temporarily raising the pressure of fuel in said auxiliary chamber by a slight depression of said piston, and fuel supply nozzles in communication 40 with said float chamber and said auxiliary chamber to discharge fuel for carbureting air in said carbureting chamber.
21. In a carbureter, two air ports, one having a constant unvarying dimension, a suction operated valve normally closing the other air port, a fuel inlet for each of said air ports, means operable by said valve for 45 varying the area of one of said fuel inlets, a cylinder and piston affording a dash pot, and means connecting the piston of said dash-pot with said valve.
22. In a carbureter of the class described, a casing affording a mixing chamber of L-shape, an auxiliary chamber communicating laterally in one side thereof, a normally open air port for said auxiliary chamber, a fuel inlet valve mounted therein, another casing member secured to said first-mentioned casing member, and the interior chamber in said second casing registering with the lower L-extension of said mixing chamber, an automatic valve and dash-pot mounted in said second-mentioned casing 50 member, a fuel inlet valve mounted therein and connected for operation by said automatic valve, a float chamber for the carbureter, connections therebetween and with said first-mentioned fuel inlet, and communications between said float chamber and said dash-pot and said fuel inlets to force fuel under pressure therethrough when said automatic valve is suddenly opened.
23. In a carbureter of the class described, a casing, a mixing chamber of L-shape formed therein, another casing secured to said first-mentioned casing and having a chamber therein registering with the L-extension of said mixing chamber, an auxiliary chamber formed in said first-mentioned casing and communicating laterally in said mixing chamber, a float chamber forming a part of said first-mentioned casing, a fuel inlet mounted in said auxiliary chamber and 55 communicating with said float chamber, fuel inlet means mounted in said second-mentioned casing and communicating with said float chamber, and dash-pot mechanism mounted in said second-mentioned casing and connected to said fuel inlets and adapted to open the inlet of said second-mentioned casing and to augment the pressure through both of said fuel inlets.
24. In a carbureter of the class described, a casing having a mixing chamber of L-shape therein, another casing secured thereto having a chamber therein registering with the L-extension of said mixing chamber, a plurality of fuel inlets for said carbureter, one mounted in said first-mentioned casing and the other in said second-mentioned casing, air inlets for each of said fuel inlets, an automatic valve for one of said air inlets, and means connected thereto 60 to augment the pressure in the fuel source leading to said fuel inlets when said automatic valve is suddenly opened.
25. In a carbureter of the class described, a carbureting chamber, an air inlet thereto, a spring thrust motion controlled valve in said air inlet, a dash-pot, a piston in said dash-pot, a piston rod rigidly connecting said piston and said air inlet valve, a fuel spray nozzle, means for feeding fuel to said 65

- nozzle from said dash-pot from a point below the piston therein, a tapered valve to control the outflow from said nozzle, means for operating said valve by said air valve, 5 a float feed chamber for the carbureter, and communication between said float chamber and said dash-pot, and from beneath the piston in the dash-pot between said dash-pot and said fuel nozzle.
- 10 26. In a carbureter of the class described, an air inlet, a suction operated air inlet valve therein, a dash-pot, a piston in said dash-pot, a float feed fuel chamber for the carbureter in communication with said dash-pot, a fuel nozzle for the float feed chamber, a carbureting chamber, a fuel spray nozzle extending from the dash-pot into the carbureting chamber, and a tapered valve controlling the outflow from said nozzle, 15 said valve disposed for operation by said air inlet valve and communicating with said dash-pot.
- 20 27. In a carbureter, a fuel supply chamber, a throttle valve, an automatically operating air valve, fuel inlet means from said supply chamber, separate means controlled respectively by said throttle and air valves
- 25 for adjusting said fuel inlet means, each valve controlled means operating independently of the other in its control of the fuel supply, whereby the operation of either means will afford a continuous fuel supply, and a secondary air valve connected for automatic operation by said automatic air valve.
- 30 28. In a carbureter, a plurality of fuel nozzles, independent means for controlling said fuel nozzles, a throttle valve, a manually operated mechanism adapted simultaneously to adjust the throttle valve and one of said nozzle controlling means, an automatically operated air valve, a second air valve, and means operated by said automatic air valve for operating the other nozzle controlling means as well as said second air valve.
- 35 In testimony whereof I have hereunto subscribed my name in the presence of two subscribing witnesses.
- 40 CHARLES L. RAYFIELD.
- 45 Witnesses:
- CHARLES W. HILLS, Jr.,
FRANK K. HUDSON.
